UNITED STATES PATENT OFFICE.

CHARLES H. DOWNES, OF JERSEY CITY, NEW JERSEY.

STYLOGRAPHIC FOUNTAIN-PEN.

SPECIFICATION forming part of Letters Patent No. 236,877, dated January 25, 1881.

Application filed November 15, 1880. (No model.)

To all whom it may concern:

Be it known that I, CHARLES H. DOWNES, of Jersey City, in the county of Hudson and State of New Jersey, have invented certain 5 new and useful Improvements in Stylographic Fountain-Pens and Fountain-Pen Holders, of which the following is a specification.

My invention relates to improvements in writing-instruments of the fountain kind; and 10 it is applicable to stylographic fountain-pens and to fountain-holders which are adapted for receiving the ordinary writing-pens.

My invention consists, mainly, in a handle for a writing-instrument which is formed of 15 two tubular ink-receptacles, one within the other, the inner receptacle being provided with apertures for receiving external air, and also with an aperture for allowing ink from the outer receptacle to flow into said inner receptacle and out of the same, for supplying the writing-point with ink, as will be hereinafter explained.

The invention also consists in novel means for adjusting the tension of the needle-spring, 20 and also for adjusting the needle to the writing-point of the point-section, as will be hereinafter explained. I attain these objects by means shown in the annexed drawings, in which—

30 Figure 1 is a diametrical section through the improved pen-holder, having a stylographic writing-point on one end and a sheath on the other end, with an ink-delivery point for an ordinary writing-pen. Fig. 2 is a sectional view of the inner ink-tube having the improved needle and spring adjusting devices applied to it. Fig. 3 is a diametrical section, showing a modification of the pen adapted for a stylographic point. Fig. 4 is another modification, 40 showing a pen and pen-sheath applied to the barrel and a very small air-tube at the upper end of the inner ink-tube.

Similar letters refer to similar parts throughout the several views.

45 In the annexed drawings, A designates the barrel or outer tube of my improved pen-handle, and B is a small tube which is applied centrally inside of the barrel A. This small tube B is perforated near its extremities, at a 50 a, for establishing a communication between its interior and the space e between it and the

outer tube or barrel A. These apertures a a allow ink to flow from the reservoir e into the tube B.

I now refer to Fig. 3, which shows a stylographic writing-point, C, applied to the handle. The inner tube, B, in this Fig. 3 passes airtight through a section, D, and has the writing-point C secured to its exposed end. The upper end of tube B is fixed to a plug, E, in the 55 end of the barrel A, on which plug is screwed a cap, F. By slightly unscrewing cap F air is admitted through aperture c into the small ink-tube B; but when the cap F is screwed home no air will be admitted through aperture 60 c. A perforated septum, d, is shown applied in the ink-space e, between the two barrels A B, which will, in a measure, support the column of ink above it when the handle is full of ink. The ink which is received into the receptacle formed by the bore of tube B flows therefrom, during the act of writing, through the writing-point C, provided air is admitted through the aperture c. This writing-point C of Fig. 3 should be provided with a needle, 70 75 which may be made adjustable, as will be hereinafter explained.

Fig. 4 shows the inner tube, B, terminated in a point, d', adapted for supplying ink to a common pen, G, fitted in a sheath, H. The 80 tube B in this figure (4) receives air from a smaller tube, B', supplied through an inlet-aperture, c, when cap F is slightly unscrewed.

Instead of the pen-sheath H and the delivery-point d', a stylographic writing-point, C, 85 like that shown in Fig. 3 may be substituted.

Fig. 1 shows my improved fountain-handle, having on one end a stylographic writing-point or point-section, and on the other end a pen-sheath, H, like the sheath shown in Fig. 90 4. Instead of this sheath H, a stylographic point-section may be substituted, which will afford a finer or a coarser line than the writing-point on the opposite end of the handle. The air is admitted into the inner ink-tube, B, 95 of the handle of Fig. 1 through a short tube, f, which may be located at any desired point between the ends of the handle. The inner ink-tube, B, of Fig. 1 passes through a packing, h, and terminates inside of the point-section C, and is provided with apertures b b, for the escape of ink into this point-section. 100

It will be seen from the above description that I dispense with the air-tube commonly used in stylographic fountain-pens, and utilize nearly the entire space within the barrel A as a reservoir for ink. I have a large external ink reservoir or feeder, e, and a smaller ink-receiver, B, from which latter the ink flows to the writing-point.

Fig. 2 shows my improved needle attachment, which may be applied on the lower end of the ink-tube B, as shown in this figure; or it may be applied inside of tube B of Fig. 3, or it may be attached to the point-section of Fig. 1. The needle b^2 is loosely applied to a tube or holder, c^2 , and provided with a head, p. The tube c^2 is screw-threaded, and is tapped into the lower end of a tube, d^2 , so that it is adjustable endwise therein. A screw-threaded pin, e^2 , is tapped through a septum, g, and is adjustable over the head of the needle b^2 , for regulating the amount of vertical play thereof. A spring, f^2 , by its recoil on the needle-head, acts to keep the needle down on its seat. The tension of this spring is regulated by adjusting the tube c^2 in the tube d^2 , and the amount of protrusion of the point of the needle beyond the writing-point is regulated by adjusting the tube d^2 up or down on the ink-tube B.

If it is desired to apply the needle attachment inside of the tube B of Fig. 3, or inside of

the point-section C of Fig. 1, the external surface of the tube d^2 may be screw-threaded, and grooves formed lengthwise in it to allow the passage of ink to the writing-point.

It will be seen that the lower extremity of the ink-reservoir e is tightly closed, thus causing the ink contained in it to pass through the lower perforation, a, into the ink-tube B before escaping from the writing-point.

The letter h in Figs. 3 and 4 designates a tight contraction about the ink-tube B, which is the equivalent of the packing h in Fig. 1, for closing the lower end of the ink-reservoir e.

What I claim as my invention is—

1. A fountain pen-holder formed of two tubes, A and B, having the chamber e closed at h, and the ink-tube B perforated at a, substantially as described.

2. A writing-instrument in combination with the packing h, the perforated ink-tube B, and the external ink-chamber formed by the outer tube or case, A, substantially as described.

3. For a fountain-pen, a needle, b^2 , loosely attached to a tube or holder, c^2 , in combination with the tube d^2 , its adjusting-pin e^2 , and tension-spring f^2 , substantially as described.

CHARLES H. DOWNES.
